UNITED STATES PATENT OFFICE.

JAMES H. DEAN, OF LUDINGTON, MICHIGAN, AND GEORGE W. BAKER, OF CHICAGO, ILLINOIS, ASSIGNORS TO NORTHWESTERN EXPANDED METAL COMPANY, OF CHICAGO, ILLINOIS, A CORPORATION OF ILLINOIS.

RIBBED METAL LATH.

Application filed February 25, 1926. Serial No. 90,540.

This invention relates to improvements in shallow ribbed metal lath formed of expanded metal and the object of the invention is to provide lath so constructed that only sufficient plaster passes through its meshes to properly key the plaster to the lath, thereby saving the excess plaster that, with lath now in use, passes through the meshes and is wasted.

10 The invention consists generally in constructions and combinations hereinafter described and particularly pointed out in the claims.

15 In the accompanying drawings forming a part of this specification—

Figure 1 is a plan view of a metal sheet properly ribbed and slotted to produce the lath constituting our invention.

20 Figure 2 is a similar view showing the sheet expanded to form our improved lath.

25 Figure 3 is a section through the lath shown in Figure 2, the section being taken on the line 3—3, and showing also the lath nailed in position on the building studding or joist and showing the position of the plaster when applied thereto.

30 In the drawings 2 represents a metal sheet provided with the longitudinal ribs 3—3 and with diagonal slits 4 and 5, the slits in the adjacent panels extending in opposite directions, as indicated in Figure 1.

35 By suitable means, not necessary to describe herein, the slotted sheet of Figure 1 is expanded to produce strands 6 and 7, the numeral 6 being used to designate the strands that are connected to the edges of the unslotted portions of the sheets and the numeral 7 being used to indicate the intermediate strands. The strands on one side of 40 a rib all extend in the opposite direction from the strands on the other side of such rib, such an arrangement necessarily resulting from the described arrangement of the slits.

45 In the expanding operation the strands are turned at an angle to the plane of the slotted sheet substantially in the manner de-

scribed in our application for Letters Patent filed March 1, 1926, Ser. No. 91,564, the expansion being effected without stretching 50 the strands.

After being thus expanded, the strands that are connected to the unslotted portions of the sheet are rolled down flat for a distance of about one-half their length so as to 55 lie in the same plane as the unslotted portions of the sheet at each side of the ribs 3, as indicated by the shading lines on Figure 2 of the drawing.

50 The bonds 8 formed by the intersecting strands 6, 7, are also by the same operation rolled down so as to stand at a slight angle to the unslotted portions of the sheet and the flat portions of the strands hereinbefore referred to, as shown in Figure 3, and such 55 angle of inclination being substantially less than that required to effect the expansion of the panels. The portions of the strands that are between the said horizontal portions and the bonds gradually change from the flat 70 plane of the unslotted portions of the sheet to the incline of the strand intersections or bonds.

75 In the finished lath the metal at each side of the ribs is flat or in the original plane of the sheet; the bonds, and the strands forming the center diamonds or meshes, stand at a slight angle thereto while the strands that connect the bonds to the unslotted portions of the sheet, at each side of the ribs, are flat, 80 or in the plane of such unslotted portion, for about one-half their length and then gradually change their angle until it is the same as the angle of the bonds.

85 Portions of the surface of the lath thus formed are flat as will be seen, while the remaining portions are at a slight angle only to the flat portions.

90 In spreading plaster over lath, the plasterer customarily sweeps his trowel, with its load of soft plaster, across the lath. The surfaces of the nearly flat strands and bonds of the lath herein described will permit only a small portion of the plaster to pass through

the meshes, as indicated in Figure 3 of the drawings.

As the strands and bonds in the expanded metal lath commonly used stand substantially on edge, the thin edges of the metal are presented to the pressure of the trowel as the plaster is swept over the surface of the lath, and an excessive amount of plaster passes through the meshes to the back of the lath. This waste of plaster is obviated by the use of our lath in which only sufficient plaster passes between the meshes to properly key or lock the plaster to the lath.

We claim as our invention:

1. A lath comprising an expanded metal sheet having a series of parallel unslotted sections extending longitudinally of the sheet with longitudinally extending ribs formed centrally in said unslotted sections and a plurality of rows of diagonally extending diamond shaped meshes arranged between each pair of unslotted sections and formed of diagonal and longitudinal strands connected by integral bonds, the diagonal mesh forming strands that merge with the unslotted sections being at their connected ends in the same plane with the unslotted metal and the bonds and intermediate strands being inclined to the plane of the sheet at an angle substantially less than that required to effect the expansion of the panels.

2. A lath comprising an expanded metal sheet having a series of parallel unslotted sections extending longitudinally of the sheet with longitudinally extending ribs formed centrally in said unslotted sections and a plurality of rows of diagonally extending diamond shaped meshes arranged between each pair of unslotted sections and formed of diagonal and longitudinal strands connected by integral bonds, the diagonal mesh forming strands that merge with the unslotted sections being at their connected ends in the same plane with the unslotted metal and the flat surfaces of the bonds and intermediate strands being approximately parallel thereto.

3. A lath comprising an expanded metal sheet having a series of parallel unslotted sections extending longitudinally of the sheet with longitudinally extending ribs formed centrally in said unslotted sections and a plurality of rows of diagonally extending diamond shaped meshes arranged between each pair of unslotted sections and formed of diagonal and longitudinal strands connected by integral bonds, the diagonal mesh forming strands that merge with the unslotted sections lying, to a point substantially midway of their length, in the same plane with the unslotted sections of the sheet.

4. A lath comprising a metal sheet hav-

ing a series of parallel unslotted sections extending longitudinally of the sheet with longitudinally extending ribs formed centrally in said unslotted sections and rows of diamond shaped meshes arranged between each pair of unslotted sections, the mesh forming strands that merge with the unslotted sections lying, to a point substantially midway of their length, in the same plane with the unslotted sections of the sheet and thence extending at a gradually changing angle, to, and merging with, the strand connecting bonds.

5. A lath comprising a metal sheet having a series of parallel unslotted sections extending longitudinally of the sheet with longitudinally extending ribs formed centrally in said unslotted sections and rows of diamond shaped meshes arranged between each pair of unslotted sections, the mesh forming strands that merge with the unslotted sections lying, to a point substantially midway of their length, in the same plane with the unslotted sections of the sheet, and thence extending, at a gradually changing angle, to, and merging with, the strand connecting bonds, and each bond and intermediate strand being angularly disposed.

6. A lath comprising a metal sheet having a series of parallel unslotted sections extending longitudinally of the sheet with longitudinally extending ribs formed centrally in said unslotted sections and rows of diamond shaped meshes arranged between each pair of unslotted sections, the mesh forming strands that merge with the unslotted sections lying, to a point substantially midway of their length, in the same plane with the unslotted sections of the sheet, and thence extending, at a gradually changing angle, to, and merging with, the strand connecting bonds, each bond and intermediate strand being angularly disposed, and having one of its edges in the same plane as the unslotted portions of the sheet.

7. An expanded sheet metal lath comprising spaced, unexpanded strips extending longitudinally of the sheet and expanded panels between the strips having rows of diagonally arranged, non-stretched strand, diamond meshes, the flat surface of the mesh-forming strands and bonds being inclined to the plane of the sheet at an angle substantially less than that required to effect the expansion of the panels, substantially as described.

8. An expanded sheet metal lath comprising spaced, unexpanded, longitudinal strips having their central portions formed into longitudinal ribs and their edge portions lying in a common plane and expanded panels between the strips each having rows of diagonally arranged, diamond meshes formed of non-stretched, diagonal and

longitudinal strands united at their intersections by integral bonds, the strands and bonds being inclined to the plane of the sheet at an angle substantially less than that required to effect the expansion of the panels and the end portions of the diagonal strands gradually merging into the common

plane of the edge portions of the strips, substantially as described.

In witness whereof we have hereunto set our hands this 11th day of February, 1926.

JAMES H. DEAN.
GEO. W. BAKER.
